UNITED STATES PATENT OFFICE.

ALLAN C. SARGENT, OF WESTFORD, MASSACHUSETTS, ASSIGNEE TO C. G. SARGENT'S SONS CORPORATION, A CORPORATION OF MASSACHUSETTS.

DRY-DUSTING MACHINE.

Application filed April 6, 1921. Serial No. 459,031.

To all whom it may concern:

Be it known that I, ALLAN C. SARGENT, a citizen of the United States, residing at Westford, in the county of Middlesex and State of Massachusetts, have invented a new and useful Dry-Dusting Machine, of which the following is a specification.

This invention relates to a machine for removing the dust from fibrous material. It can be made in such form and size as to be suitable for dry dusting asbestos or, if manufactured on a larger scale, the same principle can be applied to the dusting of wool. The principal object of the invention is to combine with a rotary dusting screen, an effective and simple means for the automatic removal of accumulated dirt at the bottom in a convenient manner.

Further objects and advantages of the invention will appear hereinafter.

Reference is to be had to the accompanying drawings in which—

Fig. 1 is a side elevation of a dry duster constructed according to this invention and suitable for operation on asbestos or wool;

Fig. 2 is an end view of the same;

Fig. 3 is a sectional view on the line 3—3 of Fig. 1;

Fig. 4 is an elevation partly broken away to show the interior construction of a modification;

Fig. 5 is an end view of the same; and

Fig. 6 is a sectional end view on the line 6—6 of Fig. 4.

In both of the forms shown, the machine embodies a casing 10 in which are located a pair of parallel shafts 11 preferably arranged at an inclination. These are driven by a driving shaft 12 having a driving pulley 13 at one end. The connection between the shaft 12 and the shafts 11 is shown as made by means of bevel gears 14.

These shafts 11 are provided with a plurality of wheels 15 on which rest rings 16 that surround a cylindrical screen 17. The two wheels 15 of each pair are so located as to support this screen and rotate it as the shafts 11 are rotated.

Inside the cylinder are a plurality of wooden lags 19 extending longitudinally and these are provided with long teeth projecting forwardly in the general direction of rotation but sticking out somewhat toward the center.

The fiber to be dusted is introduced in a

dry state through an opening at the upper end 18. The material introduced is picked up by the teeth in comparatively small quantities and carried up around and then it slides off the teeth and drops back on the bottom of the cylinder so that the process will be repeated and the fiber gradually fed down and out at the discharge end 20.

The cylinder 17 as stated is a screen preferably made of coarse mesh screen cloth. Means is usually provided for drawing out the light dust by a fan (not shown) or by a current of air induced in any desired way. However, the heavy particles sift down through the rotating cylinder and would be deposited on the bottom of the casing 10. In order to avoid the necessity of removing these heavy droppings by removing the side panels of the casing and pulling them out, the following mechanism is provided:

On the shaft 12 there is a gear 22 meshing with a gear 23 on a parallel shaft 24. On this parallel shaft is located a sprocket wheel 21 on which an endless apron 25 is mounted and by which it is driven. This apron also passes over a sprocket wheel 26 on a shaft 27 at the other end of the casing. The shaft 27 is located at a lower level than the shaft 24 and preferably the line connecting them is parallel with the axis of the cylinder 17.

I have shown also a pair of inclined walls 30 under the cylinder converging toward each other on which a considerable part of the heavy droppings are deposited and down which they are fed by gravity toward the conveyor which is located at the bottom of the chute thus formed. When this double wall is employed the wheels 15 project through it to support the cylinder above.

It will be obvious from the above that the endless conveyor apron 25 will constantly travel with its upper strand moving longitudinally under the screen. It receives the heavier matter dusted out and deposits the same in a hopper 28 at the receiving end of the duster. This provides for continuous cleaning under practically all circumstances and does away with the difficulty of cleaning out the bottom of the casing above mentioned.

It will be understood, of course, that a special feeder can be employed for introducing material into the duster and any desired means for taking it away from the

lower end but those do not constitute a part of this invention.

The description of the cylinder 17 and casing 10 and means for driving and supporting the wheels applies equally to the form shown in Figs. 4, 5 and 6 but in that form the inclined walls 30 are more essential than they are in the other and they have at the bottom of them a cylindrical 10 passage 31 located at an inclination as in the other case and having within it a screw conveyor 32. This is shown as provided with a worm wheel 33 operated by a worm 34 on the shaft 12 but, of course, any other 15 convenient means of operation can be provided within the scope of this invention.

Although I have illustrated and described only two forms of the invention I am aware of the fact that other modifications can be 20 made therein by any person skilled in the art without departing from the scope of the invention as expressed in the claims.

Therefore I do not wish to be limited to all the details of construction herein shown 25 and described but what I do claim is:—

1. In a dry duster, the combination of a screen cylinder rotatably supported, a pair of walls under the screen slanting toward the center thereof for receiving dust

and dirt through the screen and discharging it by gravity at the point where the walls converge at the bottom, a series of pairs of wheels located below but projecting through said walls for supporting said cylinder, means for positively rotating said 30 wheels, a conveyor located in position to receive the discharge down said walls, and means connected with said wheels for operating the conveyor when the cylinder rotates to remove the discharge at one end of the casing.

2. In a dry duster, the combination, of a casing, a pair of parallel shafts therein, wheels on said shafts, a transverse power shaft, means for rotating said shafts in the same direction from said power shaft, and an inclined cylindrical screen supported on said wheels to be rotated thereby, with a second transverse shaft geared to the first named shaft, an endless apron conveyor located in the casing under the screen in inclined position to receive droppings therefrom and means on the second shaft for constantly operating the apron to remove them at the receiving end of the chamber. 55

In testimony whereof I have hereunto affixed my signature.

ALLAN C. SARGENT.
